(57) CLAIM

The ornamental design for a toothbrush holder, as shown and described.

DESCRIPTION

FIG. 1 is a perspective view from the front, right of a toothbrush holder showing my new design;

FIG. 2 is an elevational view thereof from the front;

FIG. 3 is an elevational view thereof from the rear;

FIG. 4 is an elevational view thereof from the left;

FIG. 5 is an elevational view thereof from the right;

FIG. 6 is a top plan view thereof;

FIG. 7 is a bottom plan view thereof;

FIG. 8 is an exploded perspective view thereof from the front, right, shown for clarity of disclosure; and,

FIG. 9 is an elevational cut-away view thereof, taken along line 9-9 in FIG. 1.

The broken lines in figures show unclaimed portions of the toothbrush holder that form no part of the claimed design.
